UNITED STATES PATENT OFFICE.

HEINRICH GERDES, OF BERLIN, GERMANY, ASSIGNOR TO JULIUS PINTSCH, OF BERLIN, GERMANY.

GAS PLANT.

SPECIFICATION forming part of Letters Patent No. 739,665, dated September 22, 1903.

Application filed March 22, 1901. Serial No. 52,455. (No model.)

To all whom it may concern:

Be it known that I, HEINRICH GERDES, a subject of the Emperor of Germany, and a resident of Berlin, Germany, have invented 5 certain new and useful Improvements in Gas-Power Plants, of which the following is a description.

The present invention relates to gas-power plants; and it consists of the means, as hereinafter set forth, for producing, by the suction period of a four or other cycle gas-motor, just sufficient gas for the use of the motor.

In order to render the present specification easily intelligible, reference is had to the accompanying drawing, showing a sectional elevation of the plant.

The particular object of the present invention is to produce a gas-power plant having a constant gas-pressure and in which the generation of gas only takes place during the suction period of the gas-engine and in exact proportion to the gas feed necessary for the said engine. In order to attain this object, the pipe *a* leading to the gas-engine (not shown) is connected immediately to the pipe *b*, which leads through the purifier *c* and condenser *d* to the interior of the gas-generator *e*. The generator (of any suitable construction advantageously for water-gas) is provided 20 with a water-tank underneath the grate *f*. The water in the said tank being heated by the heat from the grate, and thus slowly caused to vaporize, produces sufficient steam to generate the necessary quantity of gas for 25 the suction period of the engine. Beneath the grate *f* an air-inlet opening *g* is provided, which may be adjusted to the necessary size by any suitable means, (not shown,) so as to admit just sufficient air to the generator to 30 retain the fire in the same at the proper glow heat. During the suction period of the gas-engine—*i. e.*, the period in which the piston draws in sufficient gas to cause the explosion subsequently—sufficient air and steam will 35 be drawn by suction through the grate *f* of the generator to enable the generation of a certain quantity of gas. The suction of the engine, however, will draw the gas through the pipes *b* and *a* direct to the engine, so that 40 the gas, the generation of which is dependent on the amount of suction of the engine,

will be immediately consumed by the latter. Since, however, after the suction of the engine has ceased a comparatively small amount of gas will still be developed, which might cause 55 a dangerous increase of pressure, or in any case would decrease the required vacuum, and thus impair the working of the plant, a vacuum-regulator is arranged in the pipe *a*. A vertical pipe *h* extends upwardly from the pipe *a*, and over the open end of the same is arranged a small bell *i*, which is pressed upwardly by means of a suitable spring *2*, preferably aided by a float *3*, so as to prevent the atmospheric air-pressure from destroying the 60 vacuum or rarefaction required for the proper working of the plant. This generator and regulator are subjects of my two applications, Serial Nos. 32,851 and 32,852, respectively. If now gas is drawn from the generator *e* by 65 the suction period of the gas-engine, this suction action will in a certain measure influence the bell *i* and pull the same slightly downward, this action being also aided by a spring 4 above the bell and of less strength than the 70 lower spring *2*. It will thus be seen that as the lower spring is stronger than the upper one a partial vacuum is maintained between the suction periods of the engine. As soon as the suction ceases the bell will return to 75 its normal position under the influence of its float or spring and in so doing will draw the gas developed in the generator *e* after the suction period ceased out of the said generator, thus preventing the generation of gas- 80 pressure in the plant.

The construction of the pressure-regulator forms no part of the present invention, and any suitable regulator or generator might be employed.

I wish it to be understood that I am aware that gas-power plants have been employed which involve the use of a gasometer or collecting medium having a bell counterbalanced to retain a certain vacuum; but such 95 bell has hitherto always acted as a pulsating device, the result being that a dangerously large quantity of gas was always present in the plant and that the subsequent gas generation was not regulated by the suction of the 100 engine in any way, because the interposed amount of gas stored entirely prevented any

automatic regulation of the quantity of gas generated.

In Letters Patent of the United States No. 683,034, dated September 24, 1901, I have shown and described a special form of regulator or bell adapted for use in the plant made the subject of the present application; but I do not claim herein the construction of the pressure-regulator or bell, the present application being directed broadly to the feature of exhaust means located intermediate of the gas-generator and the gas-engine and adapted to receive the after generation of gas from the generator after each suction period of the gas-engine, thus tending to maintain a partial vacuum in the connecting-pipe between suction periods.

I claim as my invention—

1. In a gas-power plant, the combination 20 with a gas-generator adapted to generate gas by the suction of a gas-engine, a pipe connecting the generator with the gas-engine

and means adapted to receive the after generation of gas from the generator, located in the connecting-pipe and tending to maintain 25 a partial vacuum therein between the suction periods of the engine, substantially as described.

2. In a gas plant, the combination with a gas-generator adapted to generate gas by the 30 suction of a gas-engine, a pipe connecting the generator with the gas-engine and pulsating means adapted to receive the after generation of gas from the generator, located in the connecting-pipe and tending to maintain a partial 35 vacuum therein between the suction periods of the engine, substantially as described.

In witness whereof I have hereunto set my hand in presence of two witnesses.

HEINRICH GERDES.
